PRESSURE GREASE GUN FILLER

David W. Hultgren and Herbert Williams,
Bozeman, Mont.

Application June 20, 1940, Serial No. 341,560

1 Claim. (Cl. 221—47.5)

This invention relates to a pressure grease gun filler, and has for one of its objects the production of a simple and efficient device for facilitating the filling of grease guns, wherein the device may be operated with a minimum amount of inconvenience.

A further object of this invention is the production of a simple and efficient pressure grease gun filler which may be operated in an upright position and the parts of which may be readily assembled or may be separated for the purpose of cleaning or replacement.

Other objects and advantages of the present invention will appear throughout the following specification and claim.

In the drawing—

Figure 1 is a side elevational view of the filler, certain parts being shown in section;

Figure 2 is a vertical sectional view, certain parts being shown in elevation;

Figure 3 is a side elevational view of the grease gun plunger constituting part of, and detached from, the grease gun shown in Figure 2;

Figure 4 is a fragmentary side elevational view partly in section of the filler showing a part of a grease gun and filler tube in section;

Figure 5 is a side elevational view of the grease gun nozzle detached from the grease gun shown in Figure 4;

Figure 6 is a side elevational view of one of the smaller sized nozzles detached from the filler.

By referring to the drawing, it will be seen that 10 designates the barrel or container which is externally threaded, as at 11 and 12, at each end of the container. A cap 13 is threaded upon the upper end of the container 10, at 11, and this cap 13 carries a threaded plunger 14 which is threaded through the cap 13. A right-angularly extending crank or handle 15 is carried by the upper end of the plunger 14, and a piston 16 is carried by the lower end of the plunger 14. The piston 16 works in the barrel or container 10, as shown in Figure 2.

The lower end of the container 10 is threaded into a base 17, which base 17 is supported by legs 18. The base is provided with a right-angle discharge elbow 19 which has threaded engagement with the base 17 and extends laterally therefrom. A tube 19^a of suitable size to fit the desired grease gun is threaded upon the elbow 19 and the outer end thereof is normally closed by a closure cap 20 when the device is not in use, to prevent the entrance of dust and dirt and also to prevent the grease from leaking out of the tube 19^a. The 55

tube 19^a or the tube 19^b may be secured to the elbow 19 or any desired size of tube may be used to accommodate all different sizes of pressure gun barrels. When filling the type of gun indicated by the numeral 21 in Figure 2, the cap and plunger 22 thereof, shown in Figure 3, are removed and the gun 21 is inserted over the open outer end of the tube 19^a. Then by rotating the plunger 14 toward the right to feed the piston 16 downwardly, the grease in the container 10 will be forced through the discharge tube 19^a thereby filling the gun 21, the gun being forced outwardly toward the outer end of the tube 19^a as the gun 21 is filled.

15 When filling the gun of the type designated at 24, in Figure 4, the nozzle 25, shown in Figure 5, is removed and the open end of the gun 24 is inserted over the open end of the tube 19^a, the ejector plunger 26 being moved to its most retracted position. As the gun 24 is filled, the gun will move in the direction of the arrow to the dotted line position.

20 Due to the fact that the container 10 is open at both ends and threaded, the container may be easily detached from the base 17 for refilling and the cap 13 may be easily and quickly attached to or removed from the upper end of the container 10. Furthermore, no special support is necessary for the filler, since the legs 18 may be set upon a bench, the ground, or any other convenient place, and the device will then be ready for operation and need not be bolted down or anchored. The threaded plunger 14 passing through the cap 13 also provides a seal to prevent dirt and dust from entering the container 10. The crank 15, at the upper end of the plunger 14, may be used to advantage as a handle when carrying the device from place to place. The tube 19^a is of a size to snugly fit within the conventional gun and the grease will not be likely to spill or run out while filling the gun in warm weather even if the grease is light enough to flow.

25 It should be understood that certain detail changes in the mechanical construction may be employed without departing from the spirit of the invention, so long as such changes fall within the scope of the appended claim.

Having described the invention, what we claim is:

30 A pressure grease gun filler of the class described comprising a container open at both ends, a cap for closing one end, a plunger carried by the cap and adapted to eject grease from the opposite end of the container, a base, said con-

tainer fitting on said base, legs for supporting the base, a grease gun filling tube depending from said base and hung between said legs and having a right-angularly extending end terminating within the contour of the base and container, an extension tube detachably secured to said right-angularly extending end and adapted to receive a grease gun for facilitating the forcing of grease into the gun from said tube and said ex-

5 tension tube, the right-angularly extending end of the first mentioned tube being shielded within the contour of the base and container in a manner whereby the first mentioned tube will be protected against contact with foreign objects while the device is not being used and after the extension tube has been disconnected.

DAVID W. HULTGREN.
